[57] CLAIM

The ornamental design for a door lever, as shown and described.

DESCRIPTION

FIG. 1 is a left side elevational view of a door lever showing my new design, the right side being a mirror image thereof;

FIG. 2 is a front elevational view thereof, the rear following the contour shown in FIGS. 1 and 5;

FIG. 3 is a top plan view thereof;

FIG. 4 is a bottom plan view thereof; and,

FIG. 5 is a reduced left, front perspective view thereof.

FIG.1

FIG.2

FIG.3

FIG.4
